Primary Examiner — John Windmuller*Assistant Examiner* — John R Yeh(74) *Attorney, Agent, or Firm* — Michael Best & Friedrich LLP(57) **CLAIM**

I claim the ornamental design for a hand tool, as shown and described.

DESCRIPTION

FIG. 1 is a perspective view of a hand tool showing my new design;

FIG. 2 is a top view thereof;

FIG. 3 is a first side thereof;

FIG. 4 is a second side thereof;

FIG. 5 is a first end view thereof; and,

FIG. 6 is a second end thereof.

The broken lines represent portions of the hand tool that form no part of the claimed design.

1 Claim, 4 Drawing Sheets
